DESIGN.

H. HACKL.

CURTAIN OR COVER.

No. 19,331.

Patented Oct. 1, 1889.

UNITED STATES PATENT OFFICE.

HEINRICH HACKL, OF VIENNA, AUSTRIA-HUNGARY, ASSIGNOR TO MILLS & GIBB, OF NEW YORK, N. Y.

DESIGN FOR A CURTAIN OR COVER.

SPECIFICATION forming part of Design No. 19,331, dated October 1, 1889.

Application filed August 14, 1889. Serial No. 320,759. Term of patent 3½ years.

To all whom it may concern:

Be it known that I, HEINRICH HACKL, of Vienna, Austria-Hungary, have invented a new and original Design for Curtains or Covers, of which the following is a specification, reference being had to the accompanying photograph, forming a part thereof.

The leading features of the design consist of a panel A, made up of a series of polygonal figures *a*, seemingly connected as a chain, and trefoil figures *a'* prominently drawn upon certain of the polygonal figures, and a panel B, constituting a lower auxiliary border, the figures *b* and *b'* composing the panel being drawn to imitate a fringe.

The border panel A incloses a plain field C, upon which field, at each end, panels D and

D' are respectively drawn. The panel D is formed somewhat to the contour of a V, and from the inclined sides of the V-panel pendant figures *d* are seemingly downwardly projected.

The panel D' is rectangular in general contour, and embraces as characteristic features small vertical panels *d'*, containing a tree-like figure, and a transverse cap panel *d''*, in which V figures *d³* and a fan figure *d⁴* are prominent.

I claim—

A design for a curtain or cover, substantially as herein shown and described.

HEINRICH HACKL.
